UNITED STATES PATENT OFFICE

127,887

DESIGN FOR A BAG RACK

Verne Garrison, Lamar, Mo.

Application March 14, 1941, Serial No. 99,601

Term of patent 3½ years

To all whom it may concern:

Be it known that I, Verne Garrison, a citizen of the United States, residing at Lamar, in the county of Barton and State of Missouri, have invented a new, original, and ornamental Design for a Bag Rack, of which the following is a specification, reference being had to the accompanying drawing, forming part thereof.

Figure 1 is a front elevational view of a bag rack, showing my new design.

Figure 2 is an end elevational view thereof.

Figure 3 is a perspective view, on a reduced scale.

I claim:

The ornamental design for a bag rack, as shown.

VERNE GARRISON.
